UNITED STATES PATENT OFFICE.

HARRY S. GREENE, OF WOONSOCKET, RHODE ISLAND, ASSIGNOR TO THE WOONSOCKET NAPPING MACHINERY COMPANY, OF WOONSOCKET, RHODE ISLAND.

NAPPING-MACHINE.

SPECIFICATION forming part of Letters Patent No. 720,018, dated February 10, 1903.

Application filed July 31, 1902. Serial No. 117,826. (No model.)

To all whom it may concern:

Be it known that I, HARRY S. GREENE, a citizen of the United States, residing at Woonsocket, in the county of Providence and State 5 of Rhode Island, have invented new and useful Improvements in Napping-Machines, of which the following is a specification.

My invention relates to improvements in cloth-napping machines, and has for its general object to provide a machine designed more especially for napping the knit stock from which the bodies of undershirts and other undergarments are formed, which stock is not only tubular in form, but is contracted 15 at intervals in its length to form the comparatively narrow waist portions usually desired in undergarments.

The invention will be fully understood from the following description and claims when 20 taken in conjunction with the accompanying drawings, in which—

Figure 1 is a view, partly in longitudinal vertical section and partly in elevation, of a portion of a napping-machine constituting 25 the preferred embodiment of my invention; Fig. 2, a section taken in the plane indicated by the broken line 2 2 of Fig. 1 looking in the direction indicated by arrow and with some of the parts partly broken away; Fig. 30 3, a detail section illustrating one means for checking the rotation of the retarding-roller which forms part of my improvements, and Fig. 4 a detail elevation of the same.

Similar letters of reference designate 35 corresponding parts in all of the several views of the drawings, referring to which—

A is the main frame of the machine; B, a transverse shaft journaled in suitable bearings in the frame; C, a napping-drum, which 40 comprises opposite spiders *a*, fixedly mounted on the shaft B, and a series of napping-rollers—*i. e.*, card-clothed or toothed rollers—*b*, disposed in a circle about the axis of shaft B and journaled in the spiders *a*; D, a tubular shaft which loosely surrounds the shaft 45 B and is provided with a pulley *c*, designed to be connected by a band (not shown) with a suitable driving means or motor; E, a spur-wheel carried by the tubular shaft and

meshed with spur-pinions *d* on the napping-rollers *b*; F, a transverse feed-roller arranged at one side of the napping-drum and preferably in a horizontal plane below that of the shaft B; G, a transverse guide-roller arranged adjacent to the roller F, and H a transverse feed-roller disposed at the opposite side of the napping-drum with reference to the rollers F and G.

All of the parts thus far described are of the ordinary construction and are operated 60 in the usual manner—that is to say, the feed-rollers F H are rotated by driving connections, which I have deemed it unnecessary to illustrate, in the direction indicated by arrows to feed the cloth or material to be napped through the machine, and the napping-drum is rotated by means (not shown) in the direction indicated by arrow No. 1 in Fig. 1, while the spur-wheel E is rotated in the direction indicated by arrow No. 2 in Fig. 1 to rotate 65 the napping-rollers *b* in the direction of the small arrows thereon incident to the rotation of the drum.

The napping-drum shown and described *per se* forms no part of my invention, and I 75 therefore desire it distinctly understood that any other suitable napping-drum may be employed without involving a departure from the scope of the invention.

My invention consists in the provision in a 80 cloth-napping machine of a transverse roller I, calculated to stretch the cloth in the direction of the width thereof—*i. e.*, open the cloth out to its full width—and a transverse roller J, calculated to retard the feed or lengthwise 85 movement of the cloth through the machine. In conjunction with the rollers I J a transverse guide-roller K is preferably employed, and said rollers I, J, and K are arranged intermediate of the feed-rollers F and H and 90 preferably above the napping-drum, as shown, for a purpose presently pointed out. As best shown in Fig. 2, the stretching-roller I is provided at opposite sides of its middle with oppositely pitched or inclined circumferential 95 ribs *e*, the inner sides of which are beveled. Said ribs are calculated incident to the rotation of the roller to stretch the cloth in the

direction of its width, or, in other words, to open the cloth out to its full width and prevent it from contracting in the longitudinal central portion of the machine. The retard-
 5 ing-roll J may be provided on its periphery with any means adapted to retard the cloth—such, for instance, as a layer of tin f, provided with apertures g. I also desire it under-
 10 stood that any suitable means may be em-
 15 ployed for retarding the rotation of the roller J or making the same rotate at a low rate of speed. For the purpose I have shown a brake-
 20 band L, Figs. 3 and 4, which is connected to the frame A and surrounds the roller at one
 25 end thereof and has its ends adjustably connected by a screw h.

According to the practice now in vogue tu-
 20 bular knit stock or material having contract-
 25 ed portions at intervals is passed through an
 30 ordinary napping-machine in the same man-
 35 ner as a single thickness of cloth. When the
 40 tubular stock or material is thus passed
 45 through an ordinary napping-machine, the
 50 napping-rollers raise or teazel a nap upon the
 55 surface of the material with which they come
 60 in contact; but they do not contact with and
 65 produce a nap on all of the surface, this be-
 70 cause as the tubular stock passes through, the
 75 under layer, being acted upon by the napping
 80 means, is stretched more than the upper layer,
 85 with the result that the upper layer becomes
 90 loose and flabby and forms large wrinkles,
 95 which permit wrinkles to form beneath them
 100 in the under layer, thus causing folds in the
 105 under layer, the inner sides of which folds
 110 cannot be reached by the napping-rollers.
 115 Frequently the wrinkles formed in the tubu-
 120 lar stock, as stated, are so large and heavy
 125 that the napping-rollers catch into them and
 130 tear the stock or goods. The contraction of
 135 the tubular stock or goods at intervals also
 140 tends to prevent the napping-rollers from
 145 acting against and producing a uniform nap
 150 on the surface of the stock or goods.

45 When a napping-machine is equipped with
 155 my improvements and a piece of tubular knit
 160 stock contracted at intervals is passed through
 165 the same in the manner shown in Fig. 1, it
 170 will be seen that the roller J by retarding the
 175 upper layer of the stock or piece of goods suf-
 180 ficiently to draw the same tight will preclude
 185 the formation of wrinkles in said upper layer,
 190 and consequently leave no place for wrinkles
 195 to form in the under layer; also, that the
 200 stock or piece of goods will be held under
 205 uniform tension, which conduces to the proper
 210 napping thereof. It will further be seen that
 215 the roll I by stretching or opening out the
 220 stock or material in the direction of the width
 225 thereof not only assures pouncing of the
 230 whole surface of the stock at the contracted
 235 portions, but also at the comparatively wide
 240 portions, with the result that a uniform nap
 245 is produced on the stock from edge to edge.

65 The rollers I, J, and K are preferably placed

above the napping-drum, as described, be-
 70 cause the stock or material does not become
 75 stretched sufficiently at its first contact with
 80 the napping-rollers to cause trouble. It is
 85 when the stock or material is between the
 90 roller I and the feed-roller H that the diffi-
 95 culties mentioned incident to the napping of
 100 tubular knit material in an ordinary napping-
 105 machine occur.

I have entered into a detailed description
 75 of the construction and relative arrangement
 80 of parts embraced in the present and pre-
 85 ferred embodiment of my invention in order
 90 to impart a full, clear, and exact understand-
 95 ing of the same. I do not desire, however, to
 100 be understood as confining myself to such spe-
 105 cific construction and arrangement of parts,
 110 as such changes or modifications may be made
 115 in practice as fairly fall within the scope of
 120 my claims.

Having described my invention, what I
 125 claim, and desire to secure by Letters Patent,
 130 is—

1. In a napping-machine, the combination
 90 of a napping-drum, means adjacent to the
 95 same for feeding two layers or thicknesses of
 100 stock, and means for retarding the passage
 105 of the outer of the layers or thicknesses of
 110 stock, and thereby preventing the formation
 115 of wrinkles in the stock. 95

2. In a napping-machine, the combination
 100 of a napping-drum, means adjacent to the
 105 same for feeding two layers or thicknesses of
 110 stock, means for retarding the passage of the
 115 outer of the layers or thicknesses of stock to
 120 prevent the formation of wrinkles in the stock,
 125 and means for stretching the stock in the di-
 130 rection of its width. 135

3. In a napping-machine, the combination
 105 of a napping-drum, means adjacent to the
 110 same for feeding two layers or thicknesses of
 115 stock, a roller having a periphery adapted to
 120 retard the outer layer or thickness of the
 125 stock, and means for retarding the rotation
 130 of the roller so as to retard the passage of the
 135 outer layer or thickness of the stock. 140

4. In a napping-machine, the combination
 140 of a napping-drum, means adjacent to the
 145 same for feeding two layers or thicknesses of
 150 stock, a roller having a periphery adapted to
 155 retard the outer layer or thickness of the
 160 stock, means for retarding the rotation of the
 165 roller so as to retard the passage of the outer
 170 layer or thickness of the stock, and a second
 175 roller equipped with means for engaging and
 180 stretching the stock in the direction of the
 185 width thereof. 190

5. In a napping-machine, the combination
 190 of a napping-drum, feed-rollers arranged at
 195 opposite sides of the same, a roller having a
 200 periphery adapted to retard the outer of two
 205 layers or thicknesses of stock on the drum,
 210 means for retarding the rotation of the roller
 215 so as to retard the passage of the outer layer
 220 or thickness of the stock, a second roller ar- 225

ranged adjacent to the retarding-roller, and equipped with means for engaging and stretching the stock in the direction of the width thereof, and a guide-roller for leading the stock from the napping-drum to the stretching-roller.

In testimony whereof I have hereunto set

my hand in presence of two subscribing witnesses.
